UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

STOCK-CUTTING MACHINE.

1,332,530.

Specification of Letters Patent.

Patented Mar. 2, 1920.

Application filed May 3, 1915. Serial No. 25,453.

To all whom it may concern:

Be it known that I, ERASTUS E. WINKLEY, a citizen of the United States, residing at Lynn, in the county of Essex and State of Massachusetts, have invented certain new and useful Improvements in Stock-Cutting Machines; and I do hereby declare the following to be a full, clear, and exact description of the invention, such as will enable others skilled in the art to which it appertains to make and use the same.

This invention relates to machines for cutting pieces or blanks from sheets or strips of material, such as leather-board, particularly such blanks as are used in the construction of heels for boots and shoes. Such blanks, of whatever shape they may be, will herein be called simply "lifts," used in an inclusive sense.

One object of the invention is to produce a machine in which the material, in the form of sheets or strips, shall be fed automatically to the cutting means, so that the machine will require no attention on the part of the operator except in providing it with a supply of material and in removing the cut pieces. To this end there is employed an arrangement in which a supply stack of strips of material is held in the machine, and as soon as one strip has been cut into lifts by the machine another strip is first moved from the stack to the line of feed and is then advanced intermittently, by longitudinal movement in this line of feed, to the cutting-means.

Another object of the invention is to provide for the discharge of the cut lifts in such a manner that they are arranged in regular stacks, so that they may be conveniently introduced, in stack form, to the feeding-means of another machine in which a further operation is to be performed upon them. To this end the machine is provided with one or more receptacles for the lifts, preferably in the form of trays provided with elongated compartments in which the blanks are discharged in stacked relation from the cutting-means, and the machine is further provided with means operated automatically to feed the trays step-by-step as

each compartment is filled, and also to substitute an empty tray for a filled tray at the proper time, so that it is necessary for the operator of the machine only to remove the filled trays and replace them with empty 55 trays.

Another object of the invention is to insure the removal of waste-pieces, where the type of cut being made produces such pieces, from the line of feed and the space between 60 or adjacent to the cutting-means. This applies particularly to the waste-piece at the end of a strip of material which is left after the last possible complete lift has been cut from it. To this end the cutting-means have 65 been arranged in such a position that it operates on sheet material held with its width in a vertical plane, so that waste-pieces between the successive cuts tend to fall away from the cutting means by gravitation. In 70 addition there is employed a device which operates automatically to release or eject the waste-piece at the end of a strip when the strip is exhausted.

Other objects of the invention, and the 75 features of construction by which the several objects are attained will be set forth herein-after, in connection with the description of the illustrated embodiment of the invention.

The preferred form of the invention is illustrated in the accompanying drawings, in which:

Figures 1, 2, 3 and 4 are, respectively, a front-elevation, a right-hand side-elevation, a left-hand side-elevation, and a plan of a machine embodying the present invention; 85

Fig. 5 is a partial front-elevation, on a larger scale than the preceding figures, showing particularly the tray-feeding mechanism; 90

Fig. 6 is a vertical section of a part of the mechanism shown in Fig. 5;

Fig. 7 is a right-hand side-elevation of the parts shown in Fig. 5; 95

Figs. 8 and 9 are vertical sections of parts of the same mechanism;

Fig. 10 is a plan of the parts shown in Fig. 5;

Fig. 11 is a plan of a part of the machine 100

including particularly the cutting instrumentalities and the mechanism for actuating them;

Fig. 12 is a left-hand side-elevation, partly in section, of the parts shown in Fig. 11;

Figs. 13, 14 and 15 are, respectively, a rear-elevation, a left-hand side-elevation, and a plan of the lift cutting means and the parts immediately associated therewith;

Fig. 16 is a left-hand elevation, partly in section, showing in detail the means for feeding the strips of sheet-material;

Fig. 17 is a partial rear-elevation, showing particularly the mechanism for actuating the feed-devices;

Fig. 18 is a right-hand side-elevation, partly in section, of the same parts;

Figs. 19 and 20 are details of the clutch for throwing the transfer-mechanism into and out of operation; and

Fig. 21 is a detail view showing the waste ejecting bar in position to drop waste out of the strip guideway.

The invention is illustrated as embodied in a machine in which heel-lifts are died out from strips of sheet-material, each strip being of sufficient width for a single row of lifts. In the illustrated embodiment of the invention, referring particularly to Figs. 11 to 16 inclusive, the dieing-out means comprise a hollow knife or die 30, having the contour of the heel-lift which is to be cut, and a cutting-block 32 by which the material is pressed against the die. The cutting-block is reciprocated, while the die is held stationary in a die-holder 34. This die-holder has oppositely inclined surfaces 36, as shown in Fig. 13, which forms a V-shaped seat for the lower curved part of the die, while the upper straight part of the die is engaged by a U-shaped clamping-member 38, this member having tongue-and-groove connections with the body 34 of the die-holder. This arrangement is such that dies of different sizes may be held in the die-holder. In order to adjust the position of the die-holder and the die, in changing from dies of one size to another, and particularly to keep the die in the proper relation with the feed-mechanism, the die-holder as a whole is movably mounted on an inclined seat 40 formed on a frame member 42 which supports the die-holder. A clamping-screw 48, threaded in a boss on the frame 42, engages an inclined upper surface on the clamping-member 38, thereby at the same time clamping the die in the die-holder and fixing the die-holder in adjusted position on the seat 40. The foregoing arrangement is such that a die of any size may be held with its left-hand edge (looking in the direction of Fig. 13) in a fixed position with relation to the path of movement of the stock-feeding means, and the inclination of the seat 40 is such that the

lower edge of the die will also be at a fixed level regardless of the size of the die, since the inclination is such as to compensate, in connection with the lateral movement of the die-holder, for the fact that the smaller dies 70 project more deeply into the V-shaped seat 36 on the die-holder.

The die 30 is provided with a discharge-tube 50, through which the cut lifts are forced, and this tube is provided, at one side, 75 with a spring 52 (Figs. 14 and 15) working in an opening in the side of the tube, this spring serving to retain lifts in stacked relation in the tube until they are discharged therefrom into the receiving-tray herein- 80 after described.

The cutting-block 32 is screwed to a collar 54, which in turn is screw-threaded upon a hollow plunger 56. The cutting-block may be adjusted on the plunger, so as to insure its proper engagement with the die by turning the collar on the plunger and fixing it in adjusted position by means of a set-screw 58 (Fig. 12), and in this way compensation will be made for the removal of the 90 edge of the die when it is sharpened, and also for removal of the surface of the cutting-block when replanned. The plunger slides in a bearing-sleeve 60 fixed on the frame of the machine, and a spring 62 (Fig. 95 12), coiled about the plunger within a recess in the bearing-sleeve, tends to force the plunger rearwardly. To move the plunger in the opposite direction and into engagement with the die, a power-shaft has a 100 crank-portion 66 (Figs. 11 and 12) upon which a roller 68 is mounted. A fast pulley 70 and a loose pulley 72 are mounted on the shaft 64, and these pulleys are connected by a belt 74, with any suitable source of power. 105 When the shaft is rotated the roller 68 intermittently engages the rear extremity of the plunger 56 and thus reciprocates it. The belt 74 is controlled by a belt-shipper 76, of ordinary form, for throwing the machine 110 into and out of operation.

In order to equalize wear over the surface of the cutting block, means is provided for rotating it at each operative stroke of the plunger. For this purpose a plate 78 115 (Figs. 11 and 12) is fixed on the plunger, this plate having ratchet-teeth at the periphery of its rear face. A lever 80 is mounted on a stud 82 on the frame of the machine, and the rear end of the lever has a 120 lug 84 in the path of movement of the roller 68. A pawl 86 is pivoted on the forward end of the lever, and its lower extremity engages the ratchet-teeth on the plate 78, being held in engagement therewith by a 125 spring 88 connecting the pawl with the lever 80. At each rotation of the power-shaft the lever 80 is rocked so as to cause the pawl to produce a partial rotation of the plate 78 and the plunger and the cutting-block. A 130

spring 90 returns the lever to normal position, and an adjustable stop-screw 92, threaded in the lever and arranged to engage a part of the frame, serves to adjust 5 the amplitude of the movement of the lever.

The stock to be cut, in the form of strips of sheet material, is fed to the dieing-out means through a feed-passage between two vertical plates 94 and 96, as shown in Figs. 10 15 and 16, a strip X being shown in feeding position. This strip rests, at its lower edge, upon a horizontal frame-member 98 to which the plates 94 and 96 are fixed, as shown in Fig. 18. The length-wise feeding 15 movements of the strip are imparted to it by a feed-dog or feed finger 100, shown particularly in Figs. 13 and 15, which is mounted on a pivot-pin 102 in a feed-slide 104. This slide moves in a guideway 106 at the rear of 20 the plate 94, and the dog works through a horizontal slot in the plate so that it may engage the front-surface of the strip X. A spring 108 tends to swing the dog rearwardly and maintain its sharpened extremity in engagement with the material. 25

To reciprocate the feed-slide 104 it is connected, by a pivot-stud 110, with a link 112. This link is pivoted as shown in Fig. 17, to one arm 114 of a bell-crank lever, of which 30 the other arm 116 is rocked, through the intermediation of parts hereinafter described, by the rotation of a cam 118. This cam is fixed on a cam-shaft 120 (see Fig. 2) which is rotated, through bevel-gears 122, by a 35 counter-shaft 124 journaled in brackets depending from the frame-member 98. A gear 126 fixed on the counter-shaft is connected, by an intermediate gear 128, with a pinion 130 on the power-shaft 64, as shown 40 particularly in Fig. 12, so that the counter-shaft 124 is rotated constantly during the operation of the machine.

The feed-mechanism just described is arranged to have an amplitude of movement 45 as great as may be necessary in the case of the largest lift desired to be produced, and, in cases where the machine is to be used for the production of smaller lifts it is necessary to arrest the feeding movement of the 50 strip when just enough material has been fed for the particular size desired. For this purpose, the machine is provided with an end-stop 134, as shown in Figs. 13, 14 and 15, that is rigid in the line of feed. The operative extremity of this stop is located just 55 in alinement with the furthermost edge portion of the die (see dotted lines Fig. 13), so that the advance of the strip is positively arrested, by engagement of its ends with this 60 stop, when the forward edge of the strip has been advanced just across the die. Since it is necessary for the stop to be removed from operative position when the cutting block is advanced toward the die, the stop is mounted 65 on a hub 136 arranged to rock upon a stud

138 fixed in a bracket 140, and a coiled spring 142 is connected with an arm 144 on the hub, this spring tending to rock the parts in a direction to return the end-stop to operative position when the block retreats. 70

It may be necessary to adjust the end-stop both in the line of feed and at right angles thereto when the size of the die is changed. For this purpose the bracket 140 has a flat base which rests against the rear surface of 75 the frame-member 42, and both this base and the frame-member are provided with slots 148 and 150, arranged at a right-angle to each other as shown in Fig. 13. A bolt 146 passes through the slots and holds the 80 bracket in adjusted position on the frame.

In order that the feeding movement of the strip of material may be arrested, in the manner just described, without injury to the material or to the feed-mechanism, a yielding coupling is provided in the latter which is shown particularly in Fig. 17. The bell-crank lever 114—116 is loosely mounted on a stud 152 supported by a horizontal extension on a bracket 153 depending from the 85 frame-member 98. An arm 154 is also mounted on a stud alongside the bell-crank lever, and this arm carries a stud 160 on which a cam-roller 156 is mounted, this roller coöperating with the feed-cam 118. 90 The arm 116 of the lever is coupled with the arm 154 by means of a hook 158, which is pivoted on the arm 116 and embraces the stud 160. A spring 162 normally forces the hook into engagement with the stud, so that 100 the bell-crank lever participates in the movements imparted to the arm 154 by the cam and the cam-roller. Whenever the feeding movement of the strip is arrested by the end-stop 134, the pressure between the 105 stud 160 and the hook 158 is increased to a predetermined point when the spring 162 yields and permits the stud to ride out of the recess in the hook, thus permitting the bell-crank lever to remain at rest while the 110 arm 164 completes its operative stroke under the influence of the cam 118. The return-movement of the arm is produced by a spring 155, and as soon as the stud 160 reaches the hook again the further movement of the arm is imparted to the bell-crank lever, thus returning the feed-mechanism to its original position. It will be seen that this construction is such that the strip 115 of material is only momentarily subjected to a predetermined longitudinal compression, and that this compression is entirely relieved, by the disengagement of the stud from the hook, before the dieing-out means operate, so that there is no tendency to 120 crowd or buckle the material while it is being cut. The combination of the end-stop and the yielding feed-mechanism is believed to be broadly new and accordingly it is 125 broadly claimed herein. 130

After a blank has been cut from the strip it is necessary to clear the remainder of the strip from the die in order that it may be again fed. For this purpose, a clearer plate 164 is mounted on studs 166 projecting from the frame-member 43, at one side of the die, as shown in Figs. 13 and 16. Springs 168, coiled about the studs, hold the clearer-plate normally in the position of Fig. 15, but permit it to yield when the cutting-block advances. When the cutting block retreats the spring 168 expands and causes the plate 164 to return the strip to its position on a plane in front of the cutting edge of the die.

The feed-dog 100 is so moved that at the completion of the feeding movement its extremity is close to the side-edge of the die, as shown in Figs. 13 and 15, and the machine is thus adapted to utilize the entire length of a strip of material so long as enough remains to form a complete lift. Since a waste-piece of greater or less length may be left, however, after the formation of the last complete lift which it is possible to cut from the strip, provision is made for discarding this waste-piece so that at the next operation of the feed-dog a fresh strip will be brought to the die and thus the machine will never operate to produce an imperfect blank. For this purpose an edge-support is provided, in the form of a horizontal bar 170 (Figs. 13 and 14) which is arranged to support the strip in the last part of its movement toward the die by engagement with the lower edge of the strip. The bar 170 rests in front of a recess 171 in the clearer plate 164 (see Figs. 14 and 21) and is carried by an arm 172, which projects from a hub 173 (see Fig. 17) arranged to turn on a rod 174 fixed on the frame of the machine. By a cam-mechanism hereinafter described the hub 173 and the arm 172 are rocked at the proper time, to move the bar 170 back into the recess 171 (see Fig. 21) so as to remove the bar 170 from its supporting engagement with the lower edge of the strip of material. Accordingly the waste-piece at the end of the strip is automatically dropped and discarded from the machine before it can be fed to the die. The weight of the parts serves to return the bar 170 from the recess to its normal supporting position. The means for timing the operation of the edge support or discarding member will be hereinafter described. Under normal operation, the bar or supporting member 170 is forced inwardly beneath the die by the periodic advancing movements of the cutting block, in the same manner as the clearer-plate 164 is actuated. The springs 168 serve in common to return the clearer-plate and the bar 170 when the cutting block retreats. Obviously, the strip is not permitted to drop during this normal

operation of the supporting bar 170 for the reason that the strip itself is also forced in and upon the die.

A supply of strips X of material is supported, in the form of a stack, at the top of the machine, as shown in Fig. 18, these strips resting on their lower edges on a horizontal supply table 175. The strips are pressed toward the plate 96 by means of followers 177 which rests on the supply table. These followers slide freely over the supply table, and are moved by cords or chains 175' attached to the bottoms of the followers and working through slots in the table as shown in Fig. 4. The cords pass over pulleys 176, and weights 178 are attached to their ends so as to move the followers and the material yieldingly forward upon the table so often as a strip is removed from the rear end of the stack. The followers are connected by a rod 180 (Fig. 4) which may be conveniently used as a handle to retract them when a fresh supply of material is to be introduced.

The rearmost strip X lies directly over the feed-passage between the plates 94 and 96, as shown in Fig. 18, and it is supported only by the engagement of its lower edge with flat springs 182 fixed in slots in the table 175 (Figs. 4, 16 and 18), so that the strip may be forced downwardly into the slot by the application of force sufficient to bend the springs 182. For the purpose of so moving the strip, the machine is provided with automatic transfer-mechanism comprising two vertically movable dogs 184, as shown particularly in Fig. 16. These dogs are pivotally mounted in slides 186, which move vertically in guideways 190 at the rear of the plate 96, and the dogs work through vertical slots in the plate so that they may engage the rear surface of the strip X, being held in engagement therewith by springs 188. The slides 186 are provided with studs 192, projecting through slots in the sides of the guideways 190, which are engaged by the forked ends of lever-arms 194, these arms being fixed, as shown in Figs. 2 and 4, upon a rock-shaft 196 journaled on the frame of the machine. This rock-shaft is moved automatically, whenever one of the strips of material has been entirely fed past the die, to cause the dogs 184 to supply a fresh strip in position to be fed by the feed-dog 100.

The power for actuating the rock-shaft 196 is derived from the counter-shaft 124, through clutch-mechanism operable automatically at the proper time. A plate 198 is fixed to the side of the gear 126, as shown in Figs. 17 and 19, so that it rotates constantly, and this plate carries the outer member 200 of a clutch of the well known Horton type. The inner member 202 of the clutch is keyed to a hub 204, which turns loosely on the counter-shaft 124 and is confined

against endwise movement by a collar 206. The inner clutch-member 202 is provided with the usual inclined recesses, as shown in Fig. 20, in which spring-pressed friction-rollers 208 are seated. These rollers are controlled, however, by a controller having a slotted sleeve 210 integral with a plate 212 which projects at the side of the clutch-members. Springs 216 connect the inner clutch-member with pins 214 projecting from the plate 212, so that the sleeve 210 is normally rotated in a direction to cause the friction rollers 208 to act, the rollers being pressed home at this time by springs 218 introduced between them and the controller-sleeve 210. Two cam-plates 220 and 222 (Fig. 17) are fixed on and rotated by the hub 204, these cam plates being in operation whenever the Horton clutch is operative. The clutch is normally held out of operation, however, the plate 212 being provided, for this purpose, with a lug 224 (Figs. 18 and 20) which is engaged by a detent-arm 226 (Figs. 17 and 18) pivoted on a stud 228 supported at the lower end of a bracket 230 depending from the frame member 98. By this engagement rotation of the clutch-controller is prevented, the clutch-rollers 208 being thereby held out of operation so that the inner clutch-member is stationary.

The action of the Horton clutch is controlled through the detent-arm 226, by means of a device in the nature of a feeler, which is moved, after each strip-feeding operation, into the feed-passage so as to ascertain whether material sufficient for another lift remains on the strip. This feeler 234, as shown by dotted lines in Fig. 18, works through an opening in the plate 96 and is carried at the upper end of an arm 236 projecting from a hub 238 mounted to turn on the rod 174. An arm 240, depending from the hub 238, carries a cam-roller 242 which engages the periphery of the other clutch member carrying plate 198. This periphery has a recessed portion 244 (see dotted lines Fig. 18) and at the proper moment in the cycle of operation of the machine the cam-roller encounters this recess and a spring 245, attached to the arm 236 tends to draw the feeler into operative position, as shown in Fig. 18. If the end of the strip X has not yet passed beyond the feeler at this time, however, this inward movement of the feeler is arrested by the material, and the Horton clutch remains inoperative. If, on the other hand, the material is exhausted the feeler moves across the feed slot into the position of Fig. 18, and acts to throw the clutch into operation, through the action of a train of mechanism which will now be described.

The arm 240 is provided, at its lower end, with a stud 246 on which a link 248 is pivoted, and this link is pivoted, in turn, to the lower end of a bar 250. The upper end

of the bar is connected, by a pivot 251, with an arm 252, this arm being integral with the detent-arm 226, all as shown in dotted lines in Fig. 18. A spring 253, connecting the arm 252 with the bracket 230, holds the parts normally in the position shown with the detent-arm in operation. The bar 250 is provided, however, with a shoulder 254 adapted to coöperate with a lug 256 projecting from the hub of the cam-plate 198. So long as the feeler 234 is prevented from entering the feed-passage the parts are held in a position in which the lug 256 does not engage the shoulder 254, but whenever the feeler enters the feed-passage, thus permitting the arm 240 to swing inwardly as shown in Fig. 18, the shoulder is brought into the path of the lug and the lug then acts to pull the bar 250 downward, a movement which is permitted by the swinging of the link 248 about the stud 246, and in this manner the detent-arm 226 is rocked out of operative position, so as to momentarily disengage it from the lug 224 and permit the Horton clutch to impart one rotation to the cam-plates 220 and 222.

The cam-plate 220 actuates the strip-transfer mechanism previously described. A cam-roller 258 (Fig. 18) engaging the periphery of the cam-plate is mounted on a lever-arm 260, which is pivoted on the rod 174 and is integral with a second arm 262. A rod 264 (Figs. 2 and 18) connects the arm 262 with an arm 266 fixed to the rock-shaft 196 by which the arms 194 are actuated. Accordingly, whenever the feeler 234 detects the exhaustion of a strip of material the transfer-mechanism acts to force a fresh strip down into the feed-passage into position to be engaged by the feed-dog 100.

The cam-plate 222 serves to actuate the strip supporting bar 170 for the purpose heretofore described. A cam-roller 270 (Fig. 17), bearing against the periphery of the cam-plate, is carried by an arm 268 which depends from and actuates the hub 173, moving the bar 170 into its recess in the clearer plate 164 and causing the waste-piece at the end of the strip to be discarded before the end of the new strip is fed to the die by the feed-finger 100.

The means for receiving the died-out lifts from the die are best shown in Figs. 1 and 4, and Figs. 6 to 10 inclusive. The blanks are discharged in stacked relation, from the discharge tube 50, into a lift receiver in the form of a tray 272 (see Fig. 4). The tray has parallel partitions 273 forming compartments in which the stacks of lifts are supported, and it is open at its rear side for the free introduction of the lifts, while the forward side is partly closed by walls 276 (see Fig. 10). In each recess a weight or follower 278 is placed, this follower being pushed ahead of the end of the stack and 130

serving to keep the lifts from falling down in the tray.

The tray is supported on a horizontal table 280, located below the supply table 175, and is confined between front and rear walls 284 and 282 (see Fig. 4) rising from the table. After one compartment in the tray has been filled it is necessary to move the tray along the table sufficiently to bring 10 the next compartment in line with the charge-tube 50, and for this purpose mechanism is employed which operates automatically. As shown in Figs. 6 and 7, the bottom of the tray is provided with a metal 15 strip 286 which is perforated at regular intervals corresponding with the width of the compartments in the tray. This strip cooperates with two pins 288 and 290, which operate to lock the tray in its various 20 operative positions, and with a third pin 292 which operates to engage the perforations and advance or feed the tray from one position to another.

The locking-pins slide vertically in blocks 25 294, which are supported by, and have sliding engagement with, two parallel-slide-bars 296 which are fixed in horizontal position beneath the table 280, as shown particularly in Figs. 6 and 8. The locking-pins 288 and 30 290 are raised and lowered at suitable times by means hereinafter described, and when in their raised positions they prevent any movement of the tray on the table. Since the width of the recesses in the tray is variable 35 according to the width of the lifts which are being produced, it is desirable to have the locking-pins adjustable in position, and accordingly they are connected together, and their position determined, by an adjusting- 40 rod 298 (Fig. 6) which passes through the blocks 294 and has right-and-left-hand screw-threaded engagement with them. This rod is mounted beneath the table, so as to be rotatable, but is restrained against lengthwise 45 movement, and it is provided at one end with a hand-wheel 300 (Fig. 4) by which it may be turned. In this manner the blocks 294 and the locking pins may be moved toward and from each other as is necessary 50 to adapt the machine for producing lifts of different sizes.

In order that the locking-pins may be raised and lowered in the blocks 294, each block is provided with depending lugs 301 55 (Fig. 6), carrying a pivot-pin 302 upon which a rocker-arm 304 is arranged to swing. This arm carries a crank-pin 306 (Fig. 8) which engages a horizontal slot in an off-set projection 308 at the lower end of 60 the locking-pin. When the arm 304 is rocked from one side to the other the crank-pin causes the locking-pin to rise and fall.

The arms 304 are actuated by engagement of their forked lower ends with a 65 horizontal rod 310 (Fig. 5). This rod is

supported, at its ends, in arms 312 fixed on a rock-shaft 314 which is journaled in brackets 315 depending from the table 280. At its right-hand end (viewing Fig. 5) the rock shaft is provided with an arm 316 carrying a cam-roller 318, which engages a cam-face 320 at the rear side of a cam-plate 322 (Figs. 2 and 5). This cam-plate is mounted on and actuated by the cam-shaft 120 hereinbefore described, this shaft being 70 extended forwardly and supported in a bracket 324 depending from the table 280, as shown particularly in Fig. 7. The cam moves the parts positively in a direction to raise the locking-pins while the opposite 80 movement is caused by a spring 325 connecting the rod 310 with the table 280.

The feeding-pin 292 is mounted to slide vertically in a block 326 (Fig. 6), which is slidably mounted on the bars 296 in the 85 same manner as the blocks 294. The adjusting rod 298, however, merely passes loosely through an opening in the block 326, which has movements thereon independent of the adjusting movements of the blocks 294. The 90 feeding-pin is raised and lowered by means in all respects similar to those by which the locking-pins are actuated, except that such means are reversed in position so that the feeding-pin falls when the locking-pins rise, 95 and vice versa. In Fig. 8 the relation of these parts is shown in a partly diagrammatic manner, the locking-pin 290 and the feeding-pin 292 being shown displaced to the left and right, respectively, of the rest 100 of the parts shown in the figure to show the different operative positions which they occupy in the same position of the actuating-rod 310.

The horizontal feeding movements in the 105 feeding-pin are produced by moving the block 326 along the slide-bars 296, and for this purpose the block is connected, by a pivot-pin 328, with a pitman 330 (Fig. 5) which, in turn, is pivoted to the upper end 110 of a lever 332. This lever is mounted, at its lower end, on a pivot 334 on the bracket 324. The lever 332 carries a cam-roller 336, which bears on the periphery of the cam-plate 322 and is held in engagement therewith by a spring 338 connecting an arm projecting laterally from the lever 332, with the table 280, as shown in Figs. 5 and 7. The cam acts to impart a return-movement positively to the block 326, while the feeding movement is imparted by the action of the spring 338, and since this feeding movement is of a yielding character injury to the machine is avoided in case the advancing movement of the tray is blocked in any accidental manner.

In order that the tray-feeding movement may be adjusted in amplitude according to the width of the lift receiving compartments in the tray, the upper end of the 130

lever 332 is provided with a curved slot, and the link 340 is pivoted to the lever 330 by a pin 342 movable in this slot (see Fig. 5). A hand-wheel 344 is threaded on the pivot-pin, 5 and serves to fix the pin in any adjusted position in the slot.

The feed-movement of the tray occurs only intermittently, at intervals varying according to the number of whole lifts required to fill one of the compartments in the tray, and in order that the feed-movement may occur at the proper time an automatic device is employed comprising a feeler adapted to enter the forward end of the 15 compartment which is being filled and to detect the moment when the follower 278 reaches this end. This feeler 346 works through an opening in the wall 284, as shown in Figs. 5, 7 and 10, and is mounted 20 on a horizontal lever 348. The lever 348 is journaled on a stud 350 depending from the table 280. The right-hand end of the lever (viewing Figs. 5 and 10) is pivoted to a rod 352, of which the rear end is pivoted to one 25 arm 354 of a bell-crank lever mounted to swing about a stud 356 on the bracket 324. The other arm 358 of the bell-crank lever is connected by a link 360, with a detent-lever 362, which swings about a pivot-stud 364 on the bracket 324. The lower end of 30 the detent-lever cooperates with a lug 370 projecting from the controlling member 372 of a Horton clutch (see Fig. 5) by which the cam-plate 322 is connected with 35 the shaft 120. This clutch is similar in construction to that previously described. It will be understood that whenever the detent is disengaged from the lug 370 the clutch causes the shaft to impart one rotation to 40 the cam-plate, thus causing the feed-mechanism to unlock the tray, feed it through one space, and then lock it again in position to receive a stack of lifts in the next vacant compartment.

45 The feeler and the detent-lever are then returned to normal position by a spring 366 which is attached at one end to a pin 368 fixed on the rod 352 and at its other end to the table 280.

50 While one tray is being filled the operator places another empty tray in position beside it on the table 280, and in order that the two trays may be fed and locked continuously, the side-walls 380 of the trays are 55 made of only one-half the thickness of the partitions 273 (see Fig. 10) so that a feed-movement of normal length will serve to move the first tray out of operative position, after its last compartment has been filled, 60 and at the same time bring the first compartment of the next following tray into position to be filled. For the same purpose the duplicate locking pins 288 and 290 are employed, so that each tray may be locked 65 both before it is brought into receiving po-

sition, and after it has been moved beyond the influence of the feed-pin and is in position to receive lifts in its last compartment.

The operation of the machine as a whole 70 will now be briefly described. The operator places an empty tray upon the table 280 over the locking-pins, with its first compartment in line with the discharge tube 50. He then draws back the followers 177, by means of the rod 180, and lays a supply of strips of material on the supply-table 175, and then permits the followers to press the strips against the plate 96. The machinery then being started by the belt-shipper 76, the 75 transfer-mechanism at once discharges a strip downwardly from the supply-table into the feed-passage. The feed-mechanism then advances this strip lengthwise into position between the die and the cutting block, 80 and the cutting-block advances so as to cause a lift to be cut from the strip. The feeding and cutting operations continue alternately, the cut lifts being gradually expelled from the discharge-tube 50 and filling a 85 compartment of a tray 272. As soon as the first strip of material has been exhausted the feeder 234 causes another operation of the transfer-mechanism, and the edge-support 90 95 100 105 110 115 120 125 130 135 140 145 150 155 2. A stock-cutting machine having, in combination, cutting means; a table on which a stack of strips of sheet-material may rest on their edges; means acting in the plane of strips for removing the endmost strip from said stack; and means acting intermittently and lengthwise of the strip for feeding the strip so removed, to the cutting-means.
- 10 3. A stock-cutting machine having, in combination, cutting-means; a guideway through which a strip of sheet-material may be fed lengthwise to the cutting-means; feeding-means comprising a feed-device 15 formed to engage and hold a strip; mechanism for reciprocating said device along said guideway; means for supplying a strip to the guideway, and means comprising a feeler adapted to engage the strip as it is advanced for controlling the operation of said supplying means.
- 15 4. A stock-cutting machine having, in combination, cutting-means; a guideway through which a strip of sheet-material may be fed lengthwise to the cutting-means; means for feeding a strip in the guideway; and a plurality of feed devices for engaging the face of the strip and pushing it into the guideway by a transverse edgewise movement.
- 20 5. A stock-cutting machine having, in combination, a cutting die; a cutting-block movable toward and from the die; means for intermittently feeding a strip of material, lengthwise, to the die; and a stop rigid in the line of feed and adjustable according to the size of the die, to be engaged by the forward end of the strip of material, and arrest the feeding movement thereof, when a sufficient amount has been fed for the operation of the die, said stop being yieldingly mounted so that it will yield to the advancing movement of the cutting-block.
- 25 45 6. A stock-cutting machine having, in combination, cutting-means; a receptacle constructed and arranged to receive the cut material from the cutting-means in the form of a stack; and mechanism including a feeler coöperating with the stack for automatically replacing said receptacle with another receptacle.
- 50 55 7. A stock-cutting machine having, in combination, cutting-means, a receptacle having a series of compartments arranged to receive the cut material from the cutting means in the form of stacks; and mechanism including a feeler coöperating with the stack 60 in one compartment to shift the receptacle and bring an empty compartment into position to receive the material.
- 65 8. A stock-cutting machine having, in combination, cutting-means; a receptacle constructed and arranged to receive the cut material from the cutting-means in the form of stacks; and mechanism including a feeler coöperating with the stack 70 in one compartment to shift the receptacle and bring an empty compartment into position to receive the material.
- 90 9. A stock-cutting machine having, in combination, cutting-means; a receptacle arranged to receive the cut material from the cutting-means in the form of stacks having a series of compartments for such stacks, and mechanism operating automatically, after one compartment has been filled, to shift the receptacle and bring an empty compartment into position to receive the material, said mechanism including a feeler which enters the receptacle and controls the operation of the mechanism by engagement with the contents of the receptacle.
- 95 10. A stock-cutting machine having, in combination, cutting-means; means for feeding strips of material to the cutting-means; a feeler for detecting automatically the exhaustion of a strip; and means, controlled by the feeler, for removing the waste-piece at the end of the strip.
- 100 11. A stock-cutting machine having, in combination, cutting-means; means for feeding a strip of material to the cutting-means with its length substantially horizontal; a support for the strip adjacent the cutting means; and means operable automatically to remove said support when the strip is exhausted and permit the waste-piece at the end of the strip to fall out of the line of feed.
- 105 12. A stock cutting machine, having, in combination, stock cutting means, a guideway for supporting stock, discarding means for supporting the stock adjacent the cutting means, and mechanism to operate the discarding means only when the stock is absent in a predetermined portion of the 110 guideway.
- 110 13. A stock-cutting machine having, in combination, means for holding and feeding sheet-material in a substantially vertical plane; a die having its axis disposed in a substantially horizontal position for cutting blanks from the sheet as so held and fed; means for receiving the blanks, from the die, in the form of a stack extending in the horizontal direction of the die axis and means 115 disposed at the outer end of the receiving means and adapted to engage the stack for removing said receiving means when filled with blanks.
- 120 14. A stock-cutting machine having, in combination, a die with a rounded contour; a die-holder with a V-shaped seat to receive the rounded part of the die; a support, for the die-holder, having an inclined seat on which the die-holder rests and along which 125
- 130

it is laterally adjustable; and means for fixing the die-holder in adjusted position on said support.

15. A stock cutting machine, having, in combination, stock cutting means, a guideway through which the strips of stock may be fed lengthwise to the cutting means, means for feeding strips to the cutting means, a magazine for supporting strips in stack formation, means for supplying strips from the end of the stack to the guideway, and mechanism for maintaining the end strip of the stack opposite the guideway.

16. A stock cutting machine, having, in combination, a cutting block, means to relatively move the die and block to cut blanks, a magazine for supporting strips of stock with the leading end of the strips positioned longitudinally not more than the width of a blank in the rear of the cutting position, a guideway in which the strips are advanced to the die, means to intermittently feed the strips in the guideway, and means operated between successive operations of the cutting die and block to transfer a strip from the magazine to the guideway in timed relation to be operated upon by the feeding means.

17. A stock cutting machine, having, in combination, stock cutting means, a magazine for supporting strips of stock in a stack, means for intermittently advancing a strip to the cutting means, means for supplying strips from the stack to the advancing means, and mechanism to automatically detect the exhaustion of a previous strip and operate the supplying means to supply the succeeding strip to the feeding means, and maintain a continuing feed of the strips.

18. A stock cutting machine, having, in combination, stock cutting means, a magazine for supporting strips in a stack, means for intermittently advancing a strip to the cutting means, means for supplying strips from the stack to the advancing means, and mechanism to automatically detect the exhaustion of a previous strip, remove any waste on the end of the previous strip, and operate the supplying means to supply the succeeding strips to the feeding means, to maintain a continuing feed of the strips, and prevent the cutting of imperfect blanks.

19. The combination of stock cutting means, a stop for positioning the stock in a definite relation to the cutting means, said stop being unyielding in the line of feed, and reciprocating feeding means for intermittently advancing the stock to the cutting means constructed and arranged to cease exerting a feeding pressure when the stock is brought into engagement with the stop.

20. The combination of stock cutting means, a stop adjacent the cutting means, and feeding mechanism including a two-part feed lever and a latch connecting the

two parts of the lever, said latch being yieldable to allow a disconnection of the parts of the lever when the stock is brought into engagement with the stop.

21. The combination of stock cutting means, a stop adjacent the cutting means, and a feeding mechanism for advancing stock to the cutting means having a feeding stroke of greater length than the width of a blank to be cut, said feeding mechanism including a two-part feed lever and a yieldable connection between them adapted to be broken when the stock is brought into engagement with the stop to allow one part to move relatively to the other.

22. A stock cutting machine, having, in combination, stock cutting means, a receptacle constructed to receive cut blanks of varying sizes in stack formation, mechanism operating automatically when the receptacle has been filled to replace it with an empty receptacle, and means to vary the replacing movement of the receptacle to accommodate different sizes of blanks.

23. A stock cutting machine, having, in combination, stock cutting means, a guideway for supporting stock, discarding means for positioning the stock adjacent the cutting means, and a stock feeler to control the operation of the discarding means when the stock has been advanced to a predetermined position relatively to the cutting means.

24. A stock cutting machine, having, in combination, stock cutting means, means for feeding stock to the cutting means, a discarding member for supporting the stock adjacent the cutting means, and means to detect a waste piece at the end of the stock and operate the discarding member to discard the waste end before it can be fed to the cutting means.

25. A stock cutting machine, having, in combination, stock cutting means, a guideway for the stock, means for feeding stock in the guideway, a feeler movable adjacent the guideway in the path of feed to engage the stock, a discarding member in the guideway, mechanism for operating the discarding member and connections between the feeler and operating mechanism constructed and arranged to operate the discarding member when the feeler does not engage the stock.

26. A stock cutting machine, having, in combination, stock cutting means, a guideway arranged in a substantially vertical plane, means for advancing a strip of stock in the guideway, a discarding member at the bottom of the guideway to support the stock adjacent the cutting means, and means to withdraw the discarding member from the guideway when a waste end piece is next to the cutting means to permit the waste end to fall out of the guideway and

- prepare for the feeding of the next strip of stock.
27. A stock cutting machine having, in combination, work cutting means, and mechanism for intermittently advancing the work into a definite relation to the cutting means comprising a stop, a feeding device for engaging the work, and means for actuating the feeding device including a coupling which is operable to be disconnected by the resistance of the work when the work is brought into engagement with the stop. 5
28. A stock cutting machine having, in combination, work cutting means, means for operating the cutting means in a continuously recurrent cycle, and mechanism for intermittently advancing the work into a definite relation to the cutting means comprising a rigid gage, a feeding device for engaging the work to advance it, means for actuating the feeding device, means for operating said actuating means in timed relation to the cutting means, and connections between the actuating means and the feeding device which are operable when the work has been advanced into engagement with the gage to discontinue the pressure of the feeding device upon the work. 10
29. A stock cutting machine having, in combination, stock cutting means; and mechanism for intermittently advancing the work into a definite relation to the cutting means comprising a work engaging feeding device, an actuating lever for said finger, a continuously operating driving arm, a yieldable coupling for connecting said arm and lever together, and a stop for positioning the work which is unyielding in the line of feed. 15
30. A stock cutting machine having, in combination, work cutting means, a stop rigid in the line of feed for positioning the work in a definite relation to the cutting means, and means comprising a reciprocating feed dog for periodically engaging the side of the work and feeding it into engagement with the stop at each working stroke, and devices to discontinue the feeding movement of the work at each working stroke when it has pressed the work against the stop with a predetermined pressure. 20
31. A stock cutting machine having, in combination, work cutting means, a stop for positioning the work in a definite relation to the cutting means, a work feeding device, means for operating the feeding device, and yielding mechanism to stop the advance of the feeding device and discontinue the feeding pressure on the work when the work has been pressed against the stop with a predetermined pressure. 25
32. A stock cutting machine having, in combination, work treating means; a stop for positioning the work in a definite posi- 30
- tion with relation to said means, and mechanism for intermittently feeding the work comprising a feeding device for engaging the work, means for actuating the feeding device, connections between the feeding device and the actuating means including a two-armed feed lever, and a coupling uniting the arms for movement in unison which is arranged to disconnect the arms when the work is moved into engagement with the stop. 35
33. A stock cutting machine having, in combination, stock cutting means, mechanism for intermittently feeding the stock to the cutting means, devices for supplying stock to the feed mechanism, means for operating the supplying devices in timed relation to the operation of the feeding mechanism, and means co-operating with the stock and controlled as to the time of operation by the position of the stock itself to automatically bring the supplying devices into operation. 40
34. A stock cutting machine having, in combination, stock cutting means, a guideway, means for feeding stock in the guideway, a feeler constructed and arranged to engage the stock as it is fed in the guideway, devices for delivering stock to the guideway, and operating mechanism connected with said feeler to actuate the stock delivering devices for supplying new stock when the stock in the guideway has been moved into a position where it will not be engaged by the feeler. 45
35. A stock cutting machine having, in combination, intermittently operated cutting means, a guideway, means for feeding stock in the guideway, a feeler constructed and arranged to project into the feed guideway, devices for delivering stock to the guideway, means to positively press the feeler into the guideway at each stroke of the cutting means, and connections between the feeler and the stock delivering devices by which said devices will be actuated when the feeler fails to engage stock in the guideway. 50
36. A stock cutting machine having, in combination, stock cutting means, a guideway for the stock, means to feed stock in the guideway, means for introducing a strip into the guideway, and strip engaging means operating automatically by the detection of the exhaustion of the strip to set the strip introducing means into operation to place a new strip in the guideway. 55
37. A stock cutting machine having, in combination, stock cutting means, means for feeding stock to the cutting means, mechanism for detecting the end of a piece of stock, and devices controlled by the detecting means for supplying a new piece of stock to the feeding means. 60
38. A stock cutting machine having, in 65

- combination, stock cutting means, means for supporting a supply of strips of sheet material in stack formation, means for intermittently feeding strips to the cutting means, mechanism to operate the cutting means to form blanks from the strips, means for automatically moving the strip from the end of the stack to the feeding means, a blank receptacle, and means to arrange the blanks in stack formation in the receptacle as they are cut.
39. A stock cutting machine having, in combination, a cutting die, a series of blank holding receptacles arranged to be placed in alinement with the die to receive the cut blanks, and means actuated by the cut blanks in one receptacle to automatically advance the receptacles to replace a filled receptacle with an empty receptacle.
40. A stock cutting machine having, in combination, cutting means, means for feeding the stock to said cutting means, means for discharging the waste at the end of the stock, a clutch for controlling the operation of said discharging means, and automatic means for detecting the waste at the end of the stock and governing the operation of said clutch.
41. A stock cutting machine having, in combination, cutting means, means for feeding the stock to said cutting means, means for supplying a new piece of stock to said feeding means, a clutch for controlling the operation of said supplying means, and means for detecting the rear end of the stock and effecting the operation of said clutch.
42. A stacking mechanism having, in combination, a receptacle, means for feeding pieces of material thereto in stack formation, and means actuated by the material in the receptacle when the receptacle is filled to replace said receptacle with an empty receptacle.
43. A stacking mechanism having, in combination, a receptacle for holding pieces of material in stack formation, means for feeding said material into one end of the receptacle, and automatic means disposed at the other end thereof and adapted to be engaged by said material for determining when the receptacle is filled.
44. A stacking mechanism having, in combination, a receptacle for holding pieces of material in stack formation, means for feeding said material thereto, means for replacing said receptacle with an empty receptacle, and mechanism including a feeler engaged by the material in the receptacle when the receptacle is filled for controlling the operation of said replacing means.
45. A stacking mechanism having, in combination, a receptacle having a plurality of compartments to receive pieces of material in the form of stacks, means for feeding
- said pieces of material to said receptacle, and automatic means operating after one compartment has been filled to shift the receptacle and bring an empty compartment into position to receive material, said last means including a feeler that enters the receptacle and controls the operation of said automatic means by engagement with the contents of the receptacle.
46. A stock cutting machine having, in combination, a die and a cutting block relatively movable in a horizontal plane, means for holding a piece of sheet material on edge above the die and cutting block, and for lowering said material into the plane of operation, and means for feeding said material intermittently into position to be cut.
47. A stock cutting machine having, in combination, a die and a cutting block relatively movable in a horizontal plane, means for holding a supply of pieces of material above the plane of operation of said die and cutting block, means for feeding said pieces of material downwardly into said plane of operation, and means disposed below said holding means and in said horizontal plane of operation for receiving the blanks cut from said pieces of material.
48. A stock cutting machine having, in combination, cutting means, a receptacle for receiving in stack formation the pieces cut thereby, and automatic means for actuating said receptacle step-by-step through a plurality of receiving positions and for locking said receptacle in said positions.
49. A stock cutting machine having, in combination, cutting means, a receptacle having a plurality of compartments for receiving in stack formation the pieces cut by said cutting means, means for actuating said receptacle to bring the several compartments successively into receiving position, and means engaged by the cut pieces as each compartment is filled for causing said actuating means to operate.
50. A stock cutting machine having, in combination, cutting means, means for feeding a strip of material thereto, discharging means for normally supporting said strip adjacent said cutting means, and means for detecting the exhaustion of said strip of material and controlling the operation of said discharging means in accordance therewith.
51. A stock cutting machine having, in combination, cutting means, means for feeding a strip of material thereto, discharging means for normally supporting said strip adjacent said cutting means, said supporting means being moved from its normal supporting position at each operation of said cutting means, and feeler mechanism periodically engaging said strip of material for detecting the length thereof and causing the discharge of the waste end of said strip from said supporting means.

52. A stock cutting machine having, in combination, a receiver for cut pieces; means for cutting a series of pieces from the end of a strip of sheet material and for transferring the cut pieces into said receiver; and automatic means for discharging the waste-piece at the rear end of the strip separately from the cut pieces.

53. A stacking mechanism having, in combination, a receptacle to receive pieces of material; means for feeding the pieces of material to said receptacle in the form of a stack; and automatic means actuated by the feeding movement of the stack with-
10 in the receptacle for shifting the receptacle laterally from its receiving position.

54. A stacking mechanism having, in combination, a receptacle to receive pieces of material; means for feeding the pieces of material to said receptacle in the form of a stack; and automatic means including a movable feeler adapted to be engaged and actuated by the stack within the receptacle for laterally transferring said stack of
20 pieces.

55. A stacking mechanism having, in combination, a receptacle to receive pieces of material; means for feeding the pieces of material to said receptacle in the form of a
30 stack; and automatic means operable when the stack of pieces in the receptacle attains a predetermined length for effecting a lateral shifting of said receptacle.

56. A stacking mechanism having, in combination, a receptacle for holding pieces of material in stack formation; means for feeding said material thereto; means for laterally shifting the receptacle; and means including a feeler engaged by the stack of
35 material in the receptacle for controlling the operation of said shifting means.

57. A stacking mechanism having, in combination, a receptacle for holding pieces of material in stack formation; means for

feeding material into one end of the receptacle; and automatic means including a feeler engaged by the forward end of the stack in the receptacle for determining when the receptacle is filled to a predetermined extent.

58. A stock-cutting machine having, in combination, cutting means; a receptacle constructed and arranged to receive the cut material from the cutting means in the form of a stack; and automatic means coöperating with the stack within the receptacle for shifting the position of said receptacle.

59. A stock-cutting machine having, in combination, cutting means; a receptacle constructed and arranged to receive the cut material from the cutting means in the form of a stack; and automatic means including a feeler engaged and actuated by the stacked material in said receptacle for laterally shifting said receptacle.

60. A stock-cutting machine having, in combination, a cutting die; a laterally movable receptacle disposed in alinement with the die to receive the cut pieces in stacked formation; and means actuated by the cut pieces in said receptacle for automatically shifting said receptacle in a lateral direction when the receptacle is filled.

61. A stock-cutting machine having, in combination, means for supporting sheet material in a substantially vertical plane; means for feeding said material; a cutting die having its axis disposed in a substantially horizontal position for cutting blanks from the material fed thereto; a receptacle for receiving the cut blanks from the die in the form of a stack and extending in the horizontal direction of the die axis; and means engaged and actuated by the stack of blanks in the receptacle for shifting said receptacle out of alinement with said die.
